UNITED STATES PATENT OFFICE.

HENRY W. PLEISTER, OF WESTFIELD, AND JOHN KARITZKY, OF GARWOOD, NEW JERSEY; SAID PLEISTER ASSIGNOR TO HENRY B. NEWHALL AND SAID KARITZKY AS-
SIGNOR TO HENRY B. NEWHALL AS EXECUTOR OF HENRY B. NEWHALL, SR., DE-
CEASED.

BOLT ANCHOR.

Application filed June 17, 1922. Serial No. 569,129.

To all whom it may concern.

Be it known that we, HENRY W. PLEISTER, a citizen of the United States, residing at Westfield, in the county of Union and State of New Jersey, and JOHN KARITZKY, a citizen of the United States, residing at Garwood, in the county of Union and State of New Jersey, have made certain new and useful Improvements in Bolt Anchors, of which the following is a specification taken in connection with the accompanying drawings.

Our invention relates to bolt anchors. More particularly it relates to a ductile shield adapted to have a portion of the shield placed under tension, and another portion under compression so that the metal of the shield will flow into the voids and irregularities of the surface of the hole within which the shield is mounted.

Our invention further relates to a ductile shield provided with a tapered and a connected cylindrical bore there being a stop or shoulder between the two bores.

Our invention further relates to such a bolt anchor in which the shield and cone, or expanding member, are formed of materials of different strength, the expanding cone being of greater hardness and less ductility than the shield.

Our invention further relates to forming the shield of some ductile material, as aluminum, brass, fibre lead or an alloy, so that when it is expanded the metal will flow, more or less, into the irregularities and voids of the wall of the hole. The expanding cone is formed of some harder material, as for example, iron, which may or may not be galvanized.

Our invention further relates to certain combinations, details of constructions, and articles of manufacture, which will be more fully hereinafter described and pointed out in the claims.

Our invention may be applied to different forms of ductile shields. We have shown in the drawings several different forms of such shields, although it is to be particularly understood that these are shown by way of example and that our invention is not to be limited thereto.

In the accompanying drawings the same

reference numerals refer to similar parts in the several figures.

Fig. 1 is a vertical section through a wall or other suitable support, showing one form of our bolt anchor located therein and prior to being expanded;

Fig. 2 is a view similar to Fig. 1, but showing the ductile shield after it has been expanded;

Fig. 3 is a horizontal section through the shield and expanding member shown in Fig. 1;

Fig. 4 is an end elevation of the shield shown in Fig. 1;

Fig. 5 is a cross-section on the line 5—5 of Fig. 3;

Fig. 6 is a side elevation of a modified form of ductile shield;

Fig. 7 is a vertical section on the line 7—7 of Fig. 6;

Fig. 8 is a vertical section through a wall or other suitable support, showing the bolt anchor of Fig. 6 in its operative or expanded position;

Fig. 9 is a side elevation of another modified form of ductile shield;

Fig. 10 is a vertical section on the line 10—10 of Fig. 9;

Fig. 11 is a vertical section through a wall or other suitable support showing the ductile shield of Fig. 9 in its operative or expanded position;

Fig. 12 is a side elevation of still another modification in which two expanding members are used;

Fig. 13 is a vertical section on the line 13—13 of Fig. 12;

Fig. 14 is a vertical section through a wall or other suitable support showing the bolt anchor of Fig. 12 in its expanded position.

Figure 15 is a vertical section through the shield and expanding member shown in Figure 2.

Our invention broadly covers a ductile shield which is adapted to be expanded by placing a portion of the shield under tension and another portion under compression.

Our invention also broadly covers a ductile shield having a tapered bore and a cylindrical bore, there being a stop or shoulder or other member stopping the expanding mem-

ber operating in the tapered bore, from 5 cooperating with the cylindrical bore except under certain conditions. This insures that there will be first a tension of the metal and an expansion at the end of the ductile shield in which the tapered bore is located. This is usually at the inner end removed 10 from the face of the wall or other suitable support 1. After a portion of the ductile shield has been expanded by the expanding member cooperating with the tapered bore, the ductile shield is then further expanded by placing another portion of the ductile shield under compression, which will cause 15 the shield to be shortened in length but increased in diameter. This results in two separate and distinct expansions of the ductile metal both of which add to the hold or grip of the bolt anchor or shield within the 20 hole 2 of the wall or other suitable support 1.

It is well known that in drilling a hole 2, in a wall or other suitable support 1, of manufactured stone or brick, cement or natural stone, there is a certain dislodgment of 25 pebbles or sand and hard particles constituting the mass. In our invention we insure that the inner end 3 of the shield 4 will fill up all these inequalities or voids in the surface of the hole 2 that lie adjacent the end 30 3. The expansion at the inner end may be made in any suitable manner, such as by the threaded cone 5 cooperating with the screw-threads upon the bolt or screw 6. This cone cooperates with a tapered bore 7 and with a 35 screw or bolt 6 which passes through the cylindrical bore 8, after having been first passed through the work 9. The parts are then in the position shown in Fig. 1.

By rotating the head 10 of the bolt 6, in 40 any suitable manner, the cone 5 is caused to cooperate with the tapered bore 7 by being drawn to the right of Fig. 1 or towards the work 9. This will then cause the cone 5 to place the metal at the end 3 under tension 45 and expand the shield 4 at that end. The expansion of the end 3 continues until the end 11 of the cone 5 contacts with the stop or shoulder 12, Fig. 3. As soon as the cone 5 reaches the stop or shoulder 12 further rotation of the bolt or screw 6 places that 50 portion of the metal of the shield 4 between the stop or shoulder 12 and the end 13, Fig. 3, under compression, which serves to slightly shorten the length of the shield 4 and at the same time increases its diameter, 55 so that throughout practically the entire circumference of the shield, first by exerting tension and then compression, the metal will flow radially and fill up the voids and irregularities in the walls of the hole 2. By forcing the metal of the ductile shield to 60 flow into these inequalities or irregularities or voids we obtain a particularly strong union or hold with the wall or other suitable support, our bolt anchor making a much 65

stronger union or hold than bolt anchors of the same size now on the market. In Fig. 2, and in some of the other figures, the expansion or flowing of the metal of the shield into the inequalities or voids of the 70 wall 2 has been purposely exaggerated to more clearly illustrate the invention.

The particular contour and shape of the ductile shield may vary. We have shown in the drawings several different forms of ductile shields. For example in Figs. 1 to 5, the ductile shield 4 is provided with a plurality of integral members or tines 15, 16 connected together by integral webs 17, 17 of less thickness than the tines 15 and 16 80 forming grooves 18, 18.

When the hole 2 is correctly drilled so that the ductile shield 4 will just fit the hole 2, the expansion shield may be expanded by simply stretching the webs 17, 17 to expand 85 the integral tines 15 and 16. In other cases, when the hole 2 is a little large, or the walls or other supports 1 are soft, and full of irregularities or voids then, the web 17 will be fractured or broken when the tines 15 and 16 90 are expanded as shown in Fig. 2.

In Figs. 6, 7 and 8, we have shown another modification of the form of the ductile shield. In this modification the ductile shield 18 is provided with two separate and distinct tines 19 and 20, having slots 21, 21 extending from the periphery to the axial bore 8. In this form of our invention, the separate and distinct tines 19 and 20 are connected together by means of a dove-tail 22 on one tine, connecting with a dove-tail slot 23 in the other tine. The operation of expanding the ductile shield 18 is the same as that previously described, except that in this form the expanding member or cone 5 moving down the tapered bore 7, will expand the ends of the tines 19 and 20, and unless the hole 2 is perfectly drilled will break or fracture the dove-tail joint 22 and 23, as shown in Fig. 8. As soon as the end 105 of the cone 11 reaches the stop or shoulder 12, the rest of the metal of the ductile shield 18 is put under compression and will shorten the shield and increase its diameter in the 110 manner fully described in connection with the first form.

In Figs. 9, 10 and 11, we have shown a still further modification of our invention, in which the ductile shield 24 is formed as one single integral member, the metal of the shield being such as to permit the expansion of the end 25 and the increase in diameter of the shield from about the point 26 to the end 27, without having tines or other parts connected by webs or other breakable members. In this form of our invention the cone 5 will place the metal in the end 25 under tension to expand it until the cone reaches the stop or shoulder 12, from which point the cone will place the metal of the shield, 115 120 125 130

between the points 26 and 27, under compression and expand it radially into the voids and inequalities of the surface of the hole 2 as shown in Fig. 11.

5 In Figs. 12, 13 and 14 we have shown another modification of our invention, in which the ductile shield 28 is formed with two tapered bores 7, 7 ending in stops or shoulders 12, 12, the two tapered bores being connected by a single cylindrical bore 29. Within the inner tapered bore 7, we mount the same conical screw-threaded cone 5. Within the other tapered bore 7 we mount an unthreaded cone 30. In this form of our invention, the bolt or screw 6 is passed through the work 9, thence through the unthreaded cone 30, cylindrical bore 29 and into the screw-threads of the cone 5. By rotating the head 10 of the bolt or nut 6, the cone 5 is caused to move down its tapered bore 7, which at the same time causes the ductile shield 28 to move up the cone 30, the work being held between the cone 30 and the head of the nut or screw 10. The 25 effect is to cause the cone 30 to also move down or cooperate with its tapered bore 7. When the end 11 of the cone 5 reaches its shoulder or stop 12, and when the end 31 of the unthreaded cone 30 reaches the shoulder or stop 12 on the right of Fig. 12, further movement along the different tapered bores 7, 7 is arrested. Further rotation of the nut or bolt 6 will then cause the metal of the shield between the stops or shoulders 30 12, 12 to be compressed, which will tend to shorten the length of the shield 28 and at the same time increase its diameter, permitting the ductile metal to fill up all the voids and inequalities within the surface of the hole 40 2 in the wall 1.

In this particular form of shield 28, we have shown it provided with a groove 32 and a breakable web 33, the same as shown in Figs. 1 and 2 of the drawings, though of course it is to be understood that the particular form of shield may be varied.

45 In Figure 15 we have shown a vertical section of Figure 2, in which the end of the conical nut 5 is shown forced past the stop 50 12 and into the cylindrical bore 8.

In all forms of our invention illustrated, the ductile shields are so formed that the expanding member or cone 5, or cones 5 and 30 of Fig. 12, can be securely held within 55 the ductile shield by friction, by simply giving them a slight tap or blow, which insures that the cones or expanding members and shields will not become disconnected from vibrations in transportation or 60 through rough handling, thereby obviating the necessity of the purchaser or jobber going over the shipment to see whether or not all the bolt anchors are properly assembled and held together and to reassemble 65 such as have come separated during transit.

While we preferably use my invention with such shields, it is of course to be understood that other forms of shields may be used and that our invention is not to be limited to those illustrated and described.

Having thus described this invention in connection with illustrative embodiments thereof, to the details of which we do not desire to be limited, what is claimed as new and what is desired to secure by Letters Patent is set forth in the appended claims.

What we claim is:—

1. A new article of manufacture comprising a ductile shield having a plurality of separated parts connected together and provided with a tapered bore and a cylindrical bore there being a shoulder between the two bores.

2. A new article of manufacture comprising a ductile shield having a plurality of separated parts connected together by breakable means and provided with a tapered bore and a cylindrical bore there being a shoulder between the two bores.

3. A new article of manufacture comprising a ductile shield having a plurality of tapered bores one at each end of the shield and an interposed cylindrical bore there being shoulders between the tapered bores and the cylindrical bore.

4. A bolt anchor comprising a ductile shield having a tapered and cylindrical bore, a conical nut adapted to enter the tapered bore, means to retard the conical nut from entering the cylindrical bore except on excessive expanding pressure, and means to cooperate with the screwthreads of the nut to operate the bolt anchor.

5. A bolt anchor comprising a ductile shield having a tapered and cylindrical bore, a conical nut adapted to enter the tapered bore, a stop to retard the conical nut from entering the cylindrical bore except on excessive expanding pressure, and means to cooperate with the screwthreads of the nut to operate the bolt anchor.

6. A bolt anchor comprising a ductile shield having both an expanding tapered bore and an expanding cylindrical bore, an expanding member adapted to enter both the tapered and cylindrical expanding bores, and means to retard said expanding member from entering the cylindrical bore except when the maximum holding effect is desired.

7. A bolt anchor comprising a ductile shield having both an expanding tapered bore and an expanding cylindrical bore, an expanding member adapted to enter both the tapered and cylindrical expanding bores, and a stop to retard said expanding member from entering the cylindrical bore except when the maximum holding effect is desired.

8. A bolt anchor comprising a ductile shield having a plurality of separated and connected expandible parts and provided

- 4
- with a tapered and cylindrical bore having a stop between the two bores, and an expanding member adapted to cooperate with the tapered bore and with said stop.
  - 5. A bolt anchor comprising a ductile shield having a plurality of expandable parts and having two tapered bores one at each end of the shield; a cylindrical bore connecting said tapered bores, shoulders or stops between the two tapered bores and the cylind-

rical bore, and two expanding members adapted to cooperate with the tapered bores and with the two stops or shoulders.

HENRY W. PLEISTER.
JOHN KARITZKY.
